UNITED STATES PATENT OFFICE.

RICHARD MONHEIM, OF BERLIN-WEISSENSEE, GERMANY.

TRANSFORMATION BOX.

Application filed November 2, 1928, Serial No. 145,861, and in Germany August 6, 1928.

This invention relates to a packing or box on the walls of which a puzzle composed of several parts of figures is arranged, to induce the public to buy the goods in the packing or box. The packing or box can after use serve as toy for children.

By the creation of new possibilities of use of such packing or box, which serve first as packing for goods to be sold and later on as a toy, advertisements printed on the packings or boxes are more frequently brought to notice of the public than the advertisements on the commonly used packings or boxes.

15 The puzzle may be connected with the packing or box in any convenient manner or printed on the same. The different parts of the figures of the puzzle are preferably arranged on different parts of the packing or 20 box which parts are adapted to be displaced the one with regard to the other.

The movable elements may be in form of strips and adapted to be shifted with regard to a stationary part of the packing or box 25 on which other parts of the figures of the puzzle are printed.

The movable parts of the figures instead of being printed on separate shiftable strips may be printed on one or more insertion 30 boxes which serve also as packings.

In order to facilitate the mutual displacement of the several parts of the figures and in order to ensure that all the elements of the figures on one box can be composed to 35 form complete figures, it is advisable to arrange the several parts of the figures on circular disks rotatably mounted on a common axle.

The same advantage is obtained if the 40 different parts of the figures are arranged on the outer surfaces of parts of a cylindrical or prismatic box said parts being adjustable the one with regard to the other.

Several embodiments of the invention are 45 shown, by way of example, in the accompanying drawings in which:—

Fig. 1 shows in top plan view a packing consisting of two boxes slidable the one in the other, the puzzle being arranged on 50 the top plate of the outer box.

Fig. 2 is a section on line A—B of Fig. 1.

Fig. 3 is a top plan view of a box with a slidable insertion certain parts of the puzzle figures being arranged on inserted boxes.

55 Fig. 4 is a section on line C—D of Fig. 3.

Fig. 5 is a section on line E—F of Fig. 6

through a box on the circular lid of which the puzzle is arranged.

Fig. 6 is a top plan view of Fig. 5.

Fig. 7 shows in elevation the side wall 60 of a cylindrical box which is partly shown in section.

Fig. 8 is a section on line G—H of Fig. 7.

The top surface of the lid 1 of the outer box of a sliding box as shown in Figs. 1 65 and 2 has an upper range of apertures 3 and a lower row of apertures 4. On the strip between the two rows of apertures the middle portions of the puzzle figures are printed, painted or otherwise represented. 70 Underneath the apertures 3 a strip 6 and underneath the apertures 4 a strip 7 is slidably guided. On the strip 6 the heads 8 of the figure and on the strip 7 the lower parts or legs of the figures are painted or 75 otherwise arranged.

By moving the slidable strips 6 and 7, the parts 5, 8, 9 of the puzzle figures can be brought into different positions with regard to the middle parts 5 of the same whereby 80 new and sometimes rather funny figures are formed.

Instead of human figures as shown in Fig. 1, figures of animals may be represented or 85 human figures and animal figures so that, for instance a human figure with an animal's head or an animal figure with a human head can be composed.

The boxes may be of any shape. As shown in Fig. 2 a second box 10 is inserted 90 into the outer box 2 the inserted box being for instance filled with chocolates.

As shown in Figs. 3 and 4 an upper row 95 of apertures 14 and a lower row of apertures 15 are arranged in each, the top plate 11 and the bottom plate 12 of the outer box 13. The middle parts 16 of the human figures are arranged between the upper row of apertures 14 and the lower row of apertures 15. In the closed box 13 two boxes 17 and 18 100 are inserted designed to hold the goods, for instance chocolate.

On the top plate 19 and on the bottom plate 20 of the inserted box 17 heads 21 are printed or painted and the lower parts 105 24 of the figures are printed on the top and bottom plates 22 and 23 of the inserted box 18.

By inserting the boxes 17 and 18 into the box 13 the parts 16, 21 and 24 of the 110 figures can be brought into the desired mutual position.

The inserted boxes 17 and 18 can be pulled out of box 13 and turned 180° so that the parts of the figures on the top and bottom plates 20 and 23 can be brought into register with the parts 16 of the figures on the top plate 11 of the outer box 13 and the parts of the figures on the top and bottom plate 19 and 22 can be brought into register with the parts 16 of the figures on the bottom plate 12 of the outer box.

Apertures or windows might also be arranged only on the top plate 11 of the outer box 13. In this case the inserted boxes 17 and 18 have parts of figures either on the top plate only or on the top and on the bottom plate.

Fig. 5 shows a box 26 of circular cross section having a lid 25 also of circular cross section. On the lid 25 two circular disks 27 and 28 are rotatably fixed by means of a rivet 29. On the lid 25 and on the disks 27, 28 parts of human or other figures are printed or painted so that the figures stand radially on the lid. The elements 30 or legs are on the lid 25, the trunks 31 on the disk 28 and the heads 32 on the disk 27.

By rotating the disks, the parts 30, 31 and 32 on the lid 25 and on the disks 27 and 28 can be brought into any desired position so that complete figures composed of corresponding or of different parts may be formed.

Fig. 7 shows a cylindrical box over each end of which a cylindrical cap 34 and 35 is placed.

On the central portion 33 of the box, trunks 36 of figures, for instance human figures, are printed or painted on the cap 34 the lower portions or legs and on the cap 35 the heads 38. As the caps 34 and 35 may be rotated with regard to the central portion 33, the different parts of the figures can be brought into different positions the one with regard to the other, the different figure-parts on one box forming complete figures.

The box may also be of polygonal cross section. In this case the caps 34, 35 must be removed before they are turned with regard to the central part 33.

50 I claim:—

1. A transformation box composed of an outer box and of several inner boxes inserted in said outer box and different parts of different figures arranged on said outer box and the top and bottom plates of said inner boxes, so that the parts of figures on said inserted boxes can be combined with the parts of the figures on the outer box in different manners if said inserted boxes are turned 180°.

2. A combined box and puzzle comprising a casing having a plurality of spaced aper-

tures on one side thereof and fragmentary figures reproduced thereon adjacent said apertures, and a container for insertion 65 within said casing, said container being provided with fragmentary illustrations on opposite sides thereof so arranged as to be visible through said apertures when positioned within said casing and cooperating with the 70 illustrations on said casing to form a completed illustration, whereby reversal of the container within said casing serves to alter the character of the illustrations.

3. A combined package and puzzle comprising a casing having an aperture in the wall thereof and having a fragmentary figure reproduced thereon adjacent said aperture, and a plurality of containers for simultaneous insertion within said casing, said containers being provided with fragmentary illustrations so arranged as to be visible through said aperture and cooperating with the fragmentary figure on said casing to form a completed illustration, whereby the 80 character of the illustration may be altered by an interchange of position of the containers within the package.

4. A combined package and puzzle comprising a casing having a plurality of spaced 90 apertures in the wall thereof and having fragmentary figures reproduced thereon adjacent said apertures, and a plurality of containers for simultaneous insertion within said casing, said containers being provided with fragmentary illustrations so arranged as to be visible through said apertures when properly positioned within said casing and cooperating with the fragmentary figures on said casing to form completed illustrations, whereby the character of the illustration's may be altered by an interchange of position of the containers within the package.

5. A combined package and puzzle comprising a casing having apertures in opposite walls thereof and having fragmentary figures reproduced thereon adjacent each aperture, and a plurality of containers for simultaneous insertion within said casing, 100 said containers being provided with fragmentary illustrations on opposite sides thereof so arranged as to be visible through said apertures when properly positioned within said casing and cooperating with the fragmentary figures on said casing to form a completed illustration, whereby the character of the illustration may be altered by an interchange of position of the containers within the package, or by reversal of either 110 container.

In testimony whereof I affix my signature.

RICHARD MONHEIM.
